UNITED STATES PATENT OFFICE.

CARL AUER, OF FRAGARIA, WASHINGTON, ASSIGNOR OF ONE-EIGHTH TO FRANK RUETH, OF SEATTLE, WASHINGTON.

MILK-BOTTLE HOLDER.

1,233,163.

Specification of Letters Patent. Patented July 10, 1917.

Application filed October 28, 1916. Serial No. 128,197.

To all whom it may concern:

Be it known that I, CARL AUER, a citizen of the United States, and a resident of Fragaria, in the county of Kitsap and State 5 of Washington, have invented a new and Improved Milk-Bottle Holder, of which the following is a full, clear, and exact description.

This invention relates to bottle holders 10 and particularly to an improved milk bottle holder and has for an object the provision of a simple, strong construction easily operated by the milkman and by the occupant of the house.

Another object in view is to provide a 15 holder for milk bottles in which a catch is utilized for preventing a reverse movement of the bottle carrying member, the catch being associated with a spring so as to 20 properly operate though arranged loosely in position.

A still further object of the invention is to provide a milk bottle holding device which is connected to the door jamb in such 25 a way that the securing means are covered and the various parts which operate are covered in a manner to prevent the operation of the device by an instrument.

In the accompanying drawings: 30 Figure 1 is a top plan view of a holder embodying the invention, the same being shown applied.

Fig. 2 is a sectional view through Fig. 1 on line 2—2.

Fig. 3 is a sectional view through Fig. 1 on line 3—3.

Fig. 4 is a detail perspective view of the catch and spring.

Fig. 5 is a plan view of the bracket, the 40 same being on a reduced scale.

Referring to the accompanying drawing by numerals, 1 indicates a door jamb of any suitable kind and 2 a door held in place by a hinge 3 in the usual manner. A bracket 45 4 is connected with the jamb 1 through the use of a clip 5 having a dovetailed way 6 arranged therein for receiving the dovetailed end 7 of bracket 4. The clip 5 is held in position by suitable screws 8 and 9, the 50 heads of which are covered by the dovetailed end 7. The end 7 is preferably made slightly tapering so that it may be slidingly fitted into position, as shown in Fig. 1, and moved out of position when door 2 is 55 opened, or may be driven tightly into posi-

tion when the bracket 4 is to remain a substantially permanent fixture. The outer or free end of the bracket is provided with a ring 10 extending on both sides of the bracket, as shown in Fig. 3, one side overlapping the flange 11 of the carrier 12 and the other flange overlapping the cap 13. Within the ring 10 a pair of slots 14 and 15 is arranged, a central aperture 16 for receiving the retaining screw 17 and apertures 60 18 and 19 for receiving screws 20 and 21 which pass through said apertures and into cap 13, whereupon cap 13 is held rigidly in place on the bracket.

As shown in Fig. 3, cap 13 is provided 70 with a hollowed-out raised portion 22 for receiving the end of spring 23, which spring bears against the catch 24 on a suitable raised portion 25 formed on the catch for holding the spring in place. Catch 24 is 75 provided with cam members 26 and 27 which are rounded on one face and square on the opposite face, whereby the webs or raised portions 28 and 29 formed integrally with the carrier 12 may strike the rounded portions of the cams and raise the catch until the catch has been passed, whereupon the spring 23 will cause the catch to snap back into position and thereby prevent a reverse movement of the carrier 12. The cams 26 80 and 27 extend through the slots 14 and 15 and move up and down in these slots according to the rotation of the carrier 12, which may be rotated in one direction but not in the opposite direction, namely, in 85 the direction of the arrow 30 (Fig. 1).

By this construction and arrangement the deliveryman may remove the empty bottle from the carrier when the parts are arranged as shown in Fig. 1 and substitute a 90 full bottle, after which he may rotate the carrier in the direction of the arrow 30 until the carrier assumes the position shown in dotted lines, whereupon the carrier is locked against a reverse movement and cannot be 95 rotated to any greater extent by reason of the fact that the extending end 31 of carrier 12 will strike the door 2. This will prevent an unauthorized person from removing the full bottle but will allow the occupant of the house to remove the bottle whenever door 2 is opened. Upon opening door 2 the full bottle is removed and an empty bottle substituted and the occupant then turns the carrier to the position shown 100 105 110

in Fig. 1, ready for the deliveryman. The carrier 12 is provided with depending walls 32 and 33 merging into a rear wall 34 and also into a flange 35 which extends preferably for the full length of the wall 32, wall 34 and also wall 33. A lug 36 is provided at the outer end of the flange 35 on wall 33 in order to prevent accidental removal of the bottle by an authorized person.

10 In order to assemble the parts, especially cap 13, the carrier 12 is provided with an aperture 37 through which a screw driver or other tool may be forced in order to apply or remove the screws 20 and 21. It will 15 be observed that the carrier may freely rotate in one direction but cannot rotate in the opposite direction and that all of the moving parts of the catch and associated mechanism are covered, thus preventing 20 an unauthorized person from tampering with the locking mechanism. As seen more particularly in Fig. 3, flange 10 is formed equally on opposite sides of the bracket 4 and the apertures 14 and 15 are identically 25 constructed, whereby when assembling the bracket with the carrier 12 the same may be assembled as shown in the drawing or the bracket may be turned over so as to fit on the opposite side of the door frame in 30 case the door swings in a reverse direction to that shown. This identical construction of both faces of the bracket 4 and associated parts allows the device to be assembled either as a right hand device or a left 35 hand device.

What I claim is:

1. A milk bottle holder comprising a bracket formed with a pair of slots, a spring actuated catch provided with a pair 40 of cams extending through said slots, and a carrier pivotally mounted on said bracket formed with projecting lugs designed to engage said cams and move the cams out of the way when moved in one direction and 45 to be stopped by the cams when moved in the opposite direction whereby the carrier can rotate in one direction only.

2. A milk bottle holder comprising a bracket formed with a pair of arc-shaped 50 slots, a catch having a pair of cam members extending through said slots, a spring for normally holding said catch against the bracket, a carrier provided with a pair of lugs adapted to engage said cams and raise 55 the same when moved in one direction, said cams having beveled faces on one side and a straight face on the opposite side so as to prevent the rotation of the carrier in one direction.

60 3. A milk bottle holder comprising a bracket formed with a horizontal surface and an upstanding annular flange on each

side of said surface, said surface being provided with a pair of slots and a plurality of apertures, a bottle carrier provided with a flange fitting within the flange on the lower face of said horizontal surface, means extending through one of said apertures and into said carrier for pivotally mounting the carrier, a catch arranged on 70 the upper face of the bracket and extending through said slots, lugs arranged on said carrier adapted to engage said catch, said catch being formed to permit the rotation of the lugs in one direction only, a cap covering said catch and fitting within the annular flange on the upper face of said horizontal surface, and retaining means extending through some of the apertures in said bracket for connecting the cap with 80 the bracket.

4. A holder for milk bottles comprising a carrier formed with an annular up-standing member, a bracket provided with a round structure extending above and below the body thereof, said ring structure surrounding said up-standing member, means for pivotally connecting said carrier with the bracket so that the up-standing member may rotate within the ring, a projection arranged on the upper part of said carrier, a catch mounted on said bracket and arranged to engage said projection, said catch having an inclined face on one side and a straight face on the opposite, whereby the projection may pass beneath the catch when moving in one direction but will be prevented rotation in the opposite direction, means for holding said catch in proper operative position, and a cap mounted 100 on said bracket covering the catch.

5. A milk bottle holder comprising a bracket provided with a ring structure at the outer end extending above and below the body of the bracket, said bracket being provided with a pair of slots positioned within the ring structure, a catch having a cross bar and a pair of cams, said cams having an inclined face on one side and a straight face on the opposite side, a spring 110 acting on said cross bar for causing the cams to normally project through said slots in said bracket, a cap covering said catch, means for holding the cap in proper position, and a carrier formed with a pair of up-standing members arranged to engage the beveled sides of the cams for raising the catch when the carrier is moved in one direction and engage the straight faces of the cams when moved in the opposite direction, whereby the carrier is locked against 115 a reverse rotary movement.

CARL AUER.
